REUBEN C. BROPHY, OF ELGIN, ILLINOIS, ASSIGNOR TO THE RANSOM & RANDOLPH COMPANY, OF TOLEDO, OHIO, A CORPORATION OF OHIO.

VACUUM CASTING DEVICE.

1,030,868.

Specification of Letters Patent.

Patented July 2, 1912.

Application filed November 10, 1909. Serial No. 527,133.

To all whom it may concern:

Be it known that I, REUBEN C. BROPHY, a citizen of the United States, residing at Elgin, in the county of Kane and State of Illinois, have invented a certain new and useful Improvement in Vacuum Casting Devices, of which the following is a full, clear, concise, and exact description, reference being had to the accompanying drawings, forming a part of this specification.

My invention relates to mechanism adapted for use in connection with vacuum casting machines, and is particularly adapted for use with machines of this class employed in the making of castings for dental work.

It is an object of my invention to improve the construction of crucible supports commonly employed in connection with vacuum casting machines of the class indicated in such a manner that the suction exerted upon the crucible is distributed upon different portions of the investment compound instead of being concentrated upon practically one portion, as has heretofore been the case.

It is the further object of my invention to construct the suction connection extending from the crucible support in such a manner that the metal which is from time to time drawn through the investment compound into the suction connection is trapped before reaching the valve in such connection. This I accomplish by leading the air exhausted from the mold through a circuitous path before it reaches the controlling valve, and in this path I place a readily removable cup into which the air and liquid metal are obliged to pass. In this manner the larger portion of the metal which is drawn from the mold through the investment compound into the suction connection is caught and congealed in the removable cup, and any portion of the metal not thus entrapped is prevented from reaching the controlling valve by the circuitous path necessarily taken by the air from such cup before reaching the controlling valve.

It is a further object of my invention to provide an automatically operated mechanism for covering the crucibles used in the casting operation by means of the operation

of the controlling valves. This mechanism is so constructed that it automatically places the cover upon the crucible when the valve is turned to exert suction upon the investment compound contained within the crucible. In this manner I provide that the entire force of the suction exerted upon the investment compound is effective in exhausting the air from the mold formed within the compound and leakage of air from the external atmosphere around the mold into the suction connection is prevented. The cover mechanism constructed in accordance with my invention is adapted to be employed either with an apparatus consisting of a single crucible support or a double crucible support, the cover being so arranged that it may coöperate with either support and be automatically released and moved to its operative position by the opening of the valve associated with the particular crucible support in use.

The several drawings illustrating my invention are as follows:

Figure 1 is a side view of my casting device in its completely assembled condition, portions of the device being sectioned to more clearly show the construction thereof. Fig. 2 is a view of the parts shown in Fig. 1 taken along the line 2, 2. Fig. 3 is a detail view of the parts shown in Fig. 1 of a modified form of means that may be employed for securing the crucible cover to the supporting lever.

Similar numerals refer to similar parts throughout the several views.

As shown in the drawings, 1 is a portion of the wall of a tank in which a vacuum may be maintained by any suitable means, not shown. The tank 1 has threaded into its wall a T 2 in the horizontal branches of which the valves 3 and 4 are threaded. The valves 3 and 4 have secured into their outer ends connections 5 and 6 which engage the T's 7 and 8 in such a manner that the oppositely disposed branches of these T's extend in a vertical direction. The connections 5 and 6 are so formed on the ends extending into the T's 7 and 8 that the openings formed through such connections extend upward through the upper walls of the

connections instead of through their ends, thus opening into the upper portions of the compartments formed within the T's 7 and 8. The lower ends of the T's 7 and 8 are closed by cups 9 and 10 screwed into the lower branches thereof and into these cups tubes 11 and 12 connected at their upper ends to the crucible supports 13 and 14 extend. These crucible supports are screwed into the upper branches of the T's 7 and 8, and the tubes 11 and 12 are of a considerably smaller outside diameter than the inside diameter of the T's 7 and 8, as a result of which a considerable open space is left around such tubes extending from the openings in the upper walls of the connections 5 and 6 into the cups 9 and 10 and thus to the lower ends of the tubes 11 and 12. The crucible support 13 is formed in the shape of a bowl and has its upper edge ground to a true surface to engage the lower ground surface of the ring 15 carried by the crucible 16. The crucible 16 has formed in its side wall a plurality of openings 17 which, together with the opening 18 formed in the bottom of the crucible, serve to permit communication between the vacuum that may be produced within the bowl 13 and the investment compound 19 contained within the crucible 16.

The T 2 has secured thereto by means of a clamp 20 an arm or bracket 21 to which is pivotally secured at 22 a lever 23, the lower end of which is adapted to be engaged by a double latch 24 pivoted at 25 to the arm 21. The upper end of the lever 23 is extended in such a manner that it may support a crucible cover 26 which is secured to the lever by means of a thumb screw 27. The crucible cover 26 is preferably lined with asbestos 27' or other similar material of a yielding nature which is adapted to withstand heat, which facilitates making a tight joint between the crucible cover 26 and the top of the crucible 16 when the cover is brought into engagement with such crucible. A spring 28 extends from a pin 29 carried by the lever 23 to a pin 30 carried by the arm 21, and for the position indicated in Fig. 1 lies to the left of the pivot 22, thus tending to move the lever 23 around to the left to bring the cover 26 into engagement with the crucible 16. The latch 24 has a downwardly extending arm terminating in a ring 24^a, and a chain 31 is provided which extends from a disk 32 secured to the valve handle 3^a in such a manner that when the valve is opened the chain is moved to the left, thereby rotating the latch 24 around to the right upon its pivot 25 and releasing the lever 23 which, under the action of the spring 28, is moved downwardly to bring the cover 26 into engagement with the crucible 16.

The crucible support 14 is of different

construction from the crucible support 13 in that its upper surface is ground to be directly engaged by the lower end of the crucible if desired, in which case the form of crucible shown at 16 could not be used on account of the side openings 17, but a modified form of crucible having only an opening or openings in the bottom would necessarily be employed. In using the crucible support 14 the lever 23 is moved around to the right, which causes the spring 28 to lie upon the right-hand side of the pivot 22, thus tending to move the lever around to the right, which motion is prevented by the lower end of such lever engaging the opposite side of the latch 24. For this condition the cover 26 is released and moved half way around upon the lever 23 so that it is in position to properly engage the crucible resting upon the support 14. The chain 31 is then unhooked from the ring 24^a and the chain 33 carried by the disk 34 secured to the handle 4^a of the valve 4 is hooked onto the ring 24^a, and this chain 33 serves when the valve 4 is opened to release the lever 23 in a manner similar to the release of the lever 23 by means of the opening of the valve 3.

In order to provide that the crucible cover 26 may accurately engage the upper surface of the crucible, the cover may be pivoted at 35 to a collar 36 adapted to be secured to the upper end of the lever 23 by means of the screw 27, as indicated in Fig. 3. In this modification the lever 23 is shown as having notches 23^a upon opposite sides thereof, which notches are adapted to receive the end of the screw 27 without clamping engagement between the screw and such lever, thus permitting a slight amount of rotary motion of the collar 36 upon the lever without, however, permitting displacement of the collar and crucible cover from their proper position. By means of this construction the crucible cover automatically assumes the proper position when it engages the top of the crucible to perfectly seal the same.

The operation of the mechanism above described is as follows: The mold desired is made in the crucible in any desired manner and provided with a sprue connection extending to the upper surface of the investment compound in which a slight cavity is formed to receive the metal to be run into the mold. The metal to be used to fill the mold is placed upon the compound in the cavity formed therein and heated sufficiently hot to liquefy the same. At this time the crucible is placed upon the crucible support, and with the liquid in thoroughly fluid condition having a proper vacuum in the tank 1, the valve 3 is opened which immediately opens communication between the vacuum in the tank 1 and the inside of the bowl 13, and

at the same time releases the crucible cover 26 so that it falls and closes the top of the crucible 16. The vacuum exerted upon the investment compound 19 through the openings 17 and 18 withdraws the air from the mold and immediately the liquid metal flows through the sprue into said mold. The purpose of covering the crucible during this operation is to prevent air from passing 5 from the external atmosphere directly through the investment compound to the inside of the bowl 13, and thus decreasing the efficiency of operation of the vacuum upon the mold. By closing the top of the crucible 10 all the vacuum produced is exerted directly upon the air contained within the mold, and such air is therefore more quickly and more thoroughly removed than if air from the external atmosphere were permitted to leak 15 through the investment compound around the mold.

It has been found in practice that a certain portion of the metal drawn into the mold is carried by the suction completely 20 through the investment compound and into the air passages in the connections between the crucible support and the vacuum tank. In the past considerable trouble has been experienced as a result of this metal working 25 through the connections referred to as far as the valve 3 and even in some instances getting into the T 2. This is particularly serious in connection with the use of apparatus of this class for dental work in the 30 making of gold or other metal inlays, bridges or plates, since it is desirable in using precious metals to recover all of the waste metal, owing to its value. By my present invention I am able to entirely prevent 35 the loss of metal in this manner, since it passes directly down from the crucible 16 out of the bowl 13 in liquid condition, and passing through the tube 11 is projected into the cup 9 where it is in large part contained and retained. If, however, under 40 some circumstances it is still fluid enough to pass with the air up around the outside of the tube 11 it is prevented from entering directly into the connection 5, since the air opening into such connection is formed in 45 the upper wall of that portion of the connection extending into the compartment formed within the T 7. In this manner the metal is retained within such compartment 50 and is not permitted to reach the passages through the connection 5 and the valve 3.

My automatic crucible covering mechanism is so constructed that it may readily be attached to and made a part of casting 55 mechanisms of the general construction of those indicated above that may be in use, since in order to secure the covering mechanism to such devices it is only necessary to open the clamp 20 to surround the T 2, and 60 by closing the clamp by means of a suitable

screw, as indicated, the covering mechanism is supported with the operating lever, the actuating spring and releasing latch in proper operating relation. Furthermore, it is only necessary to remove the usual screw 70 from the valve handle 3^a or 4^a and replace it by a special screw having an enlarged disk head 32 or 34, as the case may be, to which the chain 31 or 33 is secured.

While I have shown my invention in the 75 arrangements herein described, I do not, however, limit myself to these constructions, but desire to claim any equivalents that may suggest themselves to those skilled in the art.

What I claim is:

1. A crucible support for vacuum casting machines consisting in the combination of a bowl having a ground upper surface adapted to engage a transverse sealing surface formed near the middle of the crucible, and 80 a suction connection extending from the bowl.

2. A vacuum casting device consisting in the combination of a bowl having a ground upper surface, a crucible adapted to be contained in part in such bowl and having a lateral flange adapted to be engaged thereby, such crucible being provided with holes 90 in its walls within the bowl, and a suction connection extending from the bowl.

3. A crucible support for vacuum casting machines consisting in the combination of a bowl having a ground upper surface adapted to engage a sealing surface formed near the middle of the crucible, a suction connection extending from the bowl, a valve in such suction connection, and means for automatically covering the crucible when the valve is opened.

4. A vacuum casting device consisting in the combination of a bowl having a ground upper surface, a crucible adapted to be contained in part in such bowl and to be engaged thereby near its middle portion, such crucible being provided with holes in its walls within the bowl, a suction connection extending from the bowl, a valve in such suction connection, and means for automatically covering the crucible when the valve is opened.

5. A crucible support for vacuum casting machines consisting in the combination of a bowl having a ground upper surface adapted to engage a sealing surface formed near the middle of the crucible, a suction connection extending from the bowl, a valve in such suction connection, a crucible cover pivotally supported from such connection, a spring for moving such cover to engage the upper end of the crucible, and tripping means operated by the valve to release the cover when such valve is opened.

6. A vacuum casting device consisting in the combination of a bowl having a ground upper surface, a crucible adapted to be con- 130

4

10 tained in part in such bowl and to be engaged thereby near its middle portion, such crucible being provided with holes in its walls within the bowl, a suction connection 5 extending from the bowl, a valve in such suction connection, a crucible cover pivotally supported from such connection, a spring for moving such cover to engage the upper end of the crucible, and tripping means operated by the valve to release the cover when such valve is opened.

15 7. A vacuum casting device consisting in the combination of a crucible support, a suction tube extending downward from such support into a suction chamber, and a suction connection extending from the side of such chamber.

20 8. A vacuum casting device consisting in the combination of a crucible support, a suction tube extending downward from such support into a suction chamber, and a suction connection extending into such chamber and communicating therewith through an opening in the upper wall of such connection.

25 9. A vacuum casting device consisting in the combination of a crucible support, a suction tube extending downward from such support into a suction chamber, a suction connection extending from the side of such chamber, and a removable cup located in such chamber below such tube.

30 10. A vacuum casting device consisting in the combination of a crucible support, a suction tube extending downward from such support into a suction chamber, a suction connection extending into such chamber and communicating therewith through an opening in the upper wall of such connection, 40 and a removable cup located in such chamber below such tube.

35 11. A vacuum casting device consisting in the combination of a crucible support, a suction tube extending downward from such support into a suction chamber, a suction connection extending from the side of such chamber, and a removable cup located in such chamber below and around the lower end of such tube.

45 50 12. A vacuum casting device consisting in the combination of a crucible support, a suction tube extending downward from such support into a suction chamber, a suction connection extending into such chamber and communicating therewith through an opening in the upper wall of such connection, 55 and a removable cup located in such chamber below and around the lower end of such tube.

60 60 13. A crucible support for vacuum casting machines consisting in the combination of a bowl having a ground upper surface adapted to engage a sealing surface formed near the middle of the crucible, a suction tube

extending downward from such bowl into 65 a suction chamber, and a suction connection extending from the side of such chamber.

14. A vacuum casting device consisting in the combination of a bowl having a ground upper surface, a crucible adapted to be contained in part in such bowl and to be engaged thereby near its middle portion, such crucible being provided with holes in its walls within the bowl, a suction tube extending downward from such bowl into a suction chamber, and a suction connection extending from the side of such chamber.

15. A crucible support for vacuum casting machines consisting in the combination of a bowl having a ground upper surface adapted 80 to engage a sealing surface formed near the middle of the crucible, a suction tube extending downward from such bowl into a suction chamber, and a suction connection extending into such chamber and communicating therewith through an opening in the upper wall of such connection.

16. A vacuum casting device consisting in the combination of a bowl having a ground upper surface, a crucible adapted to be contained in part in such bowl and to be engaged thereby near its middle portion, such crucible being provided with holes in its walls within the bowl, a suction tube extending downward from such bowl into a suction chamber, and a suction connection extending into such chamber and communicating therewith through an opening in the upper wall of such connection.

17. A crucible support for vacuum casting 100 machines consisting in the combination of a bowl having a ground upper surface adapted to engage a sealing surface formed near the middle of the crucible, a suction tube extending downward from such bowl into a suction chamber, a suction connection extending into such chamber and communicating therewith through an opening in the upper wall of such connection, and a removable cup located in such chamber below 110 such tube.

18. A vacuum casting device consisting in the combination of a bowl having a ground upper surface, a crucible adapted to be contained in part in such bowl and to be engaged thereby near its middle portion, such crucible being provided with holes in its walls within the bowl, a suction tube extending downward from such bowl into a suction chamber, a suction connection extending 115 into such chamber and communicating therewith through an opening in the upper wall of such connection, and a removable cup located in such chamber below such tube.

19. A vacuum casting device consisting in the combination of a crucible support, a suction connection extending from such support, a valve in such connection, and means

for automatically covering the crucible when the valve is opened.

20. A vacuum casting device consisting in the combination of a crucible support, a suction connection extending from such support, a valve in such connection, and means secured to such connection for automatically covering the crucible when the valve is opened.

10 21. A vacuum casting device consisting in the combination of a crucible support, a suction connection extending from such support, a valve in such connection, an arm secured to such connection, a lever pivoted to such arm, a crucible cover carried by such lever, a spring tending to move the lever and cover to their operative position, and tripping mechanism operated by the valve for releasing the lever when the valve is opened.

20 22. A vacuum casting device consisting in the combination of two crucible supports, a common suction connection extending from such supports, a valve in such connection for each support, and means for automatically covering either crucible when the corresponding valve is opened.

30 23. A vacuum casting device consisting in the combination of two crucible supports, a common suction connection extending from such supports, a valve in such connection for each support, and means secured to such connection for automatically covering either crucible when released by the opening of the corresponding valve.

35 24. A vacuum casting device consisting in the combination of two crucible supports, a common suction connection extending from such supports, a valve in such connection for each support, an arm secured to such connection, a lever pivoted to such arm, a spring adapted to move the lever toward either support, a crucible cover reversibly carried by such lever, and tripping mechanism operable by either valve for releasing the lever and permitting it to move under the action of the spring toward the corresponding support.

25. In a crucible support, the combination of a bowl having an upper surface adapted to engage a corresponding surface on the crucible, the lower part of the crucible wall being separated from the inside of the bowl by an annular space, and a suction connection extending from the inside of said bowl.

55 26. A crucible support for vacuum casting machines, consisting in the combination of a bowl having a ground upper surface adapted to engage a sealing surface formed near the middle of the crucible, a suction connection extending from the bowl, and means for automatically covering the crucible when the suction is applied.

60 27. A vacuum casting device consisting in the combination of a crucible support, a suc-

tion connection extending from such support, and means for automatically covering the crucible when the suction is applied.

28. A vacuum casting device consisting in the combination of two crucible supports, a common suction connection extending from such supports, and means for automatically covering either crucible when the suction is applied to such crucible.

29. In a vacuum casting device, a crucible, a crucible support having a bowl with a surface adapted to engage said crucible, the lower part of the wall and the bottom of said crucible being separated from the inside of said bowl, and a suction connection for exhausting air from the space between said bowl and said crucible.

30. A crucible support for a vacuum casting machine comprising the combination of a bowl having a sealing surface adapted to engage a crucible placed within said bowl, the lower portion of the wall and the bottom of said crucible being separated from the inside of said bowl by a suction space, and a suction connection leading from said suction space.

31. In a vacuum casting device, the combination of a crucible having a lateral projection with a sealing surface, a bowl having a surface for engaging the sealing surface on said crucible, the lower portion of the wall and the bottom of said crucible being separated from the inside of said bowl by a suction space, and a suction connection leading from said suction space.

32. In a device of the described class, the combination of a receptacle open at its upper end only, a closely fitting cover adapted to close the mouth of said receptacle, a core of investment material, means for suspending said core from said cover within and at a distance from the walls of said receptacle, an exhaust duct adapted to communicate between said receptacle and a vacuum chamber, and an air cock for controlling the escape of air from said receptacle to said vacuum chamber.

33. In a device of the described class, the combination of a receptacle, a closely fitting cover adapted to close the mouth of said receptacle, a core of investment material, means for suspending said core from said cover within and at a distance from the walls of said receptacle, an exhaust duct adapted to communicate between said receptacle and a vacuum chamber, and an air cock for controlling the escape of air from said receptacle to said vacuum chamber.

34. In a dental appliance, the combination with a receptacle having a bowl-shaped body and a stem, of a ring insertible within said body, the upper portion of the ring and body being adapted to have an air-tight engagement, the lower portion of the ring

being formed with radially extending perforations.

35. A dental casting apparatus including a hollow body open at both ends, and an in-
5. vestment flask insertible within the hollow body having openings in the side and the bottom, the upper end of the flask having air tight engagement with the hollow body.

In witness whereof, I hereunto subscribe my name this 6th day of November, A. D., 1909.
